UNITED STATES PATENT OFFICE.

HOY HOWARD, OF MANSFIELD, OHIO.

SUSPENDER-END ATTACHMENT.

SPECIFICATION forming part of Letters Patent No. 330,488, dated November 17, 1885.

Application filed July 29, 1885. Serial No. 172,966. (No model.)

To all whom it may concern:

Be it known that I, HOY HOWARD, a citizen of the United States, residing at Mansfield, in the county of Richland and State of Ohio, have invented certain new and useful Improvements in Suspender-End Attachments, of which the following is a specification, reference being had therein to the accompanying drawings, in which—

10 Figure 1 represents an elevation of a buckle having my suspender-end attachment. Fig. 2 shows a similar view with the head-stud removed. Fig. 3 represents a plan of the blank from which my buckle is made. Figs. 4, 5, 15 and 6 show the same in different stages of its manufacture. Fig. 7 shows a side view of a buckle provided with a spring to cover the head of the stud. Fig. 8 shows a modification.

In making my buckle or slide I prefer to 20 use a blank, A, of sheet metal of the form shown in Fig. 3, the lower end, a, of which is first turned at right angles to the body, as shown in Fig. 4, and is afterward bent round, as shown in Fig. 5, so as to make a short tube 25 at right angles to the body of the buckle. This may then be set in a proper die, and by means of a suitable punch or tool the outer end of the tube is swaged outward, as shown in Fig. 6, to form a head, a', of which the tube forms the 30 neck or shank; or the shank of a rivet may be inserted in the tube, leaving the head outside, as shown in Fig. 8; or a flat disk may be soldered on the end of the tube. With a buckle or slide made in this or in any convenient manner I propose to use a peculiar-shaped ring, C, 35 provided with a horizontal part, c, to receive the suspender-end, and a loop, c', at its top having a narrow neck, c''. This loop is made of such a size as to loosely fit the tube or stud a, and the opening between the loop and the 40 body of the ring is a little smaller than the size of said tube or stud. By this construction a suspender-end attachment may be made that will be found very useful, and having a 45 great advantage over the ordinary snap-hook now generally used, which, as is well known, is constantly pulling out and tearing the lining of the vest, which objections are overcome by my invention, and at the same time the 50 device is more slight and durable.

The operation is so obvious that it hardly needs description, and it is sufficient to say that to remove the ring it is pushed upward, which causes the neck of the loop to expand and allow the large part of the ring to pass upward under the head of the stud, so that the head can readily be slipped out, or, by a reverse movement, the neck of the loop opens and the ring descends, leaving the loop fast around the tube or stud a.

Although I have shown a buckle and ring, it is evident that a slide or analogous article of suspender-fittings may be substituted for the buckle without departing from the spirit of my invention; and where I use the word 65 "buckle" I mean to be understood as considering slides or analogous articles as the equivalents of the buckle shown. In some cases I intend to use a spring, S, to cover the head a' of the stud, which will tend to prevent the 70 slight wear caused by the head of the stud.

What I claim as new is—

1. As an improved article of manufacture, a suspender-end attachment, substantially as described, formed from sheet metal, and provided with a round shank, with or without a head integrally connected at its upper end to the plate from which it is formed, and open at the lower side, as set forth.

2. The combination, with a suspender attachment, substantially as described, provided with a stud, a, formed out of sheet metal, with or without a head, and integrally connected at its upper side with the plate from which it is formed, and open at its lower side, of a ring, 85 C, having a loop and neck, and a spring, S, having its upper end firmly fixed to said attachment, and its lower end loosely bearing on the stud to prevent wearing of the garment, as set forth.

In testimony whereof I affix my signature, in presence of two witnesses, this 18th day of July, 1885.

HOY HOWARD.

Witnesses:

W. L. SEWELL,
HAMILTON KERR.
